UNITED STATES PATENT OFFICE.

WALTER O. SMITH AND JOSEPH E. GRENACHE, OF NEW BEDFORD, MASSACHUSETTS,
ASSIGNORS TO REE-NU-IT ELECTRIC MANUFACTURING COMPANY, OF NEW BED-
FORD, MASSACHUSETTS.

RENEWABLE FUSE.

1,407,706.

Specification of Letters Patent. Patented Feb. 28, 1922.

Application filed September 7, 1918. Serial No. 253,074.

To all whom it may concern:

Be it known that we, WALTER O. SMITH and JOSEPH E. GRENACHE, citizens of the United States, residing at New Bedford, in 5 the county of Bristol and State of Massachusetts, have invented certain new and useful Improvements in Renewable Fuses, of which the following is a specification.

This invention relates to an improved renewable fuse and has as its primary object to provide a construction wherein firm and effectual electrical connections will be provided and maintained to thus overcome the defects of inefficient contacts for the fuse 15 link with attendant heating of the fuse.

The invention has as a further object to provide a construction wherein direct electrical connection will be formed between the terminals of the fuse link and the ferrules 20 of the fuse and wherein the said terminals will be wedged in engagement with the ferrules and thus firmly held to make electrical connection therewith.

A still further object of the invention is 25 to provide a fuse employing suitable wedge members for binding the terminals of the fuse link in electrical contact with the ferrules of the fuse and wherein said wedge members may be adjustably shifted and rigidly held in engagement with the terminals for thus establishing and maintaining a 30 rigid contact between the terminals and the fuse ferrules.

The invention has as a further object to 35 provide a fuse wherein the gases created by the blowing of the fuse link will be permitted to readily escape from the fuse.

And a still further object is to provide a fuse which will be characterized 40 by simplicity and inexpensiveness of construction, which may be readily used in lieu of the ordinary fuse of similar type and will thus be adapted to eliminate a greater portion of the usual expense for fuse main- 45 tenance, and wherein the fuse link may be readily inserted within the fuse and properly connected with the ferrules thereof.

Other and incidental objects will appear 50 during the course of the detailed description of the invention. In the drawings, wherein we have illustrated the preferred embodiment of the invention, and wherein similar reference characters designate corresponding parts throughout the several views:

Figure 1 is vertical sectional view show-

ing our improved fuse, this view being on an enlarged scale in order to clearly bring out the structural details of the fuse.

Figure 2 is an enlarged elevation illustrating one end of the fuse broken away 60 and shown in section at right angles to the plane of the section of Figure 1,

Figure 3 is a detail perspective view showing one of the wedge members employed,

Figure 4 is a fragmentary sectional view 65 showing the manner in which the fuse link is inserted in the fuse.

Figure 5 is a perspective view showing a slightly modified form of link,

Figure 6 is a view similar to Figure 5 and 70 showing a further modified form of link,

Figure 7 is a vertical sectional view showing, on an enlarged scale, a modified form of fuse,

Figure 8 is an end view of the fuse, 75

Figure 9 is a perspective view illustrating the ferrule plug employed in connection with the modified form of fuse, and

Figure 10 is a perspective view showing the fuse link employed in connection with 80 the modified form of fuse.

In carrying the invention into effect we employ a barrel or receptacle 10. This barrel may be formed of fiber or other suitable insulating material and preferably threaded upon the ends of the barrel are annular ferrules 11 held against displacement by suitable locking pins 12. The ferrules are preferably constructed of copper or brass. Formed in each of said ferrules substantially midway of its length is a pair of oppositely disposed chordal shoulders 13 and, as will be observed upon reference to Figure 1 of the drawings, the ends of the barrel 90 abut these shoulders for limiting the ferrules in their inward movement upon the barrel when threaded thereon. Between each pair of shoulders is defined an intermediate slot 14 and, as also shown in Figure 1, these slots are disposed in register. The 100 slots are formed with flat parallel side walls providing contact surfaces 15 and the shoulders 13 are also formed with flat outer faces providing contact surfaces 16 at opposite sides of the slots.

Removably fitted within the barrel 10 is a fuse link including a fuse ribbon 17 which, intermediate of its ends, is preferably provided with a reduced portion or web 18. Soldered or otherwise connected to each 110

end of the fuse link is a pair of terminals 19. These terminals are preferably formed of copper and, at their outer ends, the terminals of each pair are bent to provide oppositely directed lateral lugs 20. As will be noted, all of these lugs occupy a common plane and are of a length to be freely received through the slots 14 of the ferrules 11. Consequently, the lugs at one end of the fuse link may be inserted through the slot of either of the ferrules in the manner suggested in Figure 4 of the drawings, and the link then shifted longitudinally through the barrel 10, when said pair of lugs may then be inserted through the slot of the other of the ferrules. In this position, the link is then given a half turn to dispose the pairs of lugs in position engaging over the shoulders 13 of the ferrules fitting against the contact surfaces 16 of said shoulders. The terminals 19 of each pair are spaced apart a distance corresponding to the width of each of the slots 14. Consequently, the shanks of these terminals will, when the lugs 20 are moved into position engaging over the shoulders, engage the side walls of the slots, fitting against the contact surfaces 15. As will be seen, the fuse link may be readily inserted within the fuse with a minimum of difficulty so that when the link becomes blown, a new link may be easily substituted therefor.

Removably fitted within the outer ends of the ferrules are wedge members, each including an annular head plate or disc 21 of a diameter somewhat less than that of each of the ferrules and formed on one side of said plate or otherwise connected thereto, is a diametric wedge block 22. The wedge blocks are received within the slots 14 of the ferrules between the terminals of the fuse link while the head plates 21 overlie the shoulders 13 of the ferrules. Removably threaded within the outer ends of the ferrules to engage the head plates 21 of the wedge members, are followers in the form of closure plugs 23. Upon their inner sides, these plugs are provided with diametric grooves 24 which communicate with central passages 25 formed axially through them. Upon their outer sides they are formed with nicks or openings 26 in which a screw driver or other suitable tool may be engaged for adjusting the followers within the ferrules.

As will now be readily understood, the threaded followers or plugs 23 may be screwed into the ferrules for shifting the wedge members inwardly without rotating them, and consequently forcing the blocks 22 of the wedge members into the slots 14 where the blocks will act to tightly bind the shanks of the link terminals against the contact surfaces 15, while the head plates 21 of the wedge members will move to en-

gage the lugs 20 of the terminals and tightly bind said lugs against the contact surfaces 16. A firm and direct electrical contact will thus be provided between the terminals of the fuse link and the ferrules and since 70 loosening of the terminals can occur only by displacement of the wedge members, such firm contact will be maintained by the followers acting to lock the wedge members in adjusted position. We accordingly provide an arrangement whereby heating of the fuse due to ineffectual electrical connection of the fuse link or the development of looseness in such connection, will be overcome. In this connection it is to be observed, as 80 particularly shown in Figure 1 of the drawings, that the corners of the shoulders 13 of the ferrules, at the junction of the contact surfaces 15 and 16, are rounded in order to prevent cutting of the terminals of the 85 fuse link when the wedge members are adjusted inwardly therebetween. The ribbon 17 of the fuse link will, of course, burn at the web 18 therein and this web is provided in order that a minimum amount of gas may 90 be given off within the barrel 10. However, it will be noted that any gas so given off within the barrel may flow through the slots 14, it being observed by particular reference to Figure 2 of the drawings, that 95 the wedge blocks are somewhat shorter than said slots. From the slots 14 the gases will then flow around the head plates 21 of the wedge members to the grooves 24 and thence out through the passages 25. Escape of the 100 gases will thus be freely permitted.

In Figure 5 of the drawings we have illustrated a somewhat modified form of fuse link. In this modification a fuse ribbon 27 is employed. This ribbon is provided intermediate of its ends with a reduced web 28 as in the preferred construction. Soldered or otherwise connected to the ends of the ribbon are preferably copper terminals 29 and 30. The terminal 29 is provided with a lateral lug 31 while the terminal 30 is straight. Consequently, this terminal may be inserted through the slots 14 of the ferrules 11 of the fuse to engage the lug 31 with one of the shoulders 13 of one of said ferrules when the terminal 30 may then be bent over, as shown in dotted lines, to form a lug engaging one of the shoulders of the other of said ferrules.

In Figure 6 of the drawings we have 120 shown a further modified form of fuse link. In this modification, a fuse ribbon 32 is employed. This ribbon is provided intermediate of its ends with a reduced web 33, as in the prior modification. Soldered or otherwise secured to opposite ends of the ribbon are preferably copper terminals 34 and 35 respectively. The terminal 34 is formed with oppositely offset arms 36 at the outer ends of which are formed oppositely directed 130

lateral lugs 37. The terminal 35 is formed with oppositely offset arms 38 similar to the arms 36 but these arms 38 are straight. Consequently, the link may, as will be 5 readily understood in view of the preceding description, be readily inserted through the barrel of the fuse when the arms 38 may then be bent over to form lugs similar to the lugs 37 of the arms 36. By oppositely offsetting the arms 36 and 38, these arms will 10 be adapted to engage the contact surfaces 15 of the slots 14 of the ferrules.

In Figures 7, 8 and 9 of the drawings, we 15 have illustrated a somewhat modified form of fuse, this fuse being of the knife blade type. Referring now more particularly to these figures, a barrel or receptacle 39 is employed, this barrel being similar to the barrel 10 of the preferred construction.

20 Threaded upon the ends of the barrel are ferrules 40 held against accidental displacement by pins 41. The ferrules 40 are identical with the ferrules 11 of the preferred construction with the exception that the ferrules 40 are externally threaded at their 25 outer extremities. Formed within the ferrules are shoulders 42 defining slots 43, the side walls of which provide contact surfaces 44, while the outer faces of the shoulders 30 provide contact surfaces 45.

Removably fitted through the barrel is a fuse link preferably of the type shown in detail in Figure 10 of the drawings. This link includes a fuse ribbon 46 provided intermediate of its 35 ends with a reduced web 47. The end portions of the ribbon are coated in any approved manner with copper to provide terminals 48 and, as shown in Figure 7 of the drawings, one of these terminals is engaged 40 with the contact surfaces 44 and 45 of one of the shoulders of one of the ferrules while the other terminal is engaged with corresponding contact surfaces of one of the shoulders of the other ferrule.

45 Removably fitted within the outer ends of the ferrules are wedge members having heads 49 which, while fitting snugly within the ferrules may, nevertheless, be slidably moved therein. Upon their inner sides these 50 heads are provided with diametric wedge blocks 50 fitting within the slots 43 of the ferrules and extending from the outer sides of said heads are blades 51. These blades are preferably resilient and sufficiently flexible 55 to make a good contact. Removably threaded over the outer extremities of the ferrules are followers in the form of clamping rings or collars 52 provided with flanges 53 engaging over the outer ends of the 60 heads 49. The collars are provided with

openings or notches 54 for receiving a spanner wrench or other suitable tool and as will now be clear, said collars may be adjusted upon the ferrules for shifting the wedge blocks 50 into the slots 43 and for 65 fastening the members in place. These blocks will accordingly tightly bind the terminals 48 of the fuse link in contact with the adjacent contact surfaces 44 of the ferrules while the heads will be moved to engage the lugs formed from the ends of the terminals 48 for clamping these lugs in engagement with the adjacent contact surfaces 45 of the ferrules. Firm electrical connection will thus be established and maintained 70 between the link and the ferrules. Gases created within the barrel 39 when the web 47 of the ribbon fuses, will flow through the slots 43 and around the heads 49 to emerge at the outer ends of the ferrules. 80 Such gases will accordingly encounter the flanges 53 of the collars 52 to be directed by said flanges inwardly toward the blades 51 to prevent damage to equipment.

Having thus described the invention, what 85 is claimed as new is:

1. A fuse comprising a barrel, a ferrule fixed on each end of the barrel and each having an internal flat-sided slot, a fuse link extending through the barrel and having 90 bendable terminals each projecting into the slot in the adjacent ferrule, flat-sided wedge members each having a block standing in a slot alongside a terminal and a head standing within the outer end of the ferrule and 95 bearing against the extremity of a terminal, and a member screwed to said outer end and contacting with said head for urging the wedge member inward.

2. In a fuse, the combination of a barrel, 100 a ferrule fast on each end thereof and each having internal shoulders defining a transverse slot and having the outer end of its body threaded, and a fuse link standing within said barrel and having its terminals 105 each passing through a slot and bent down onto the outer face of a shoulder in the adjacent ferrule, a wedge member at each end of the barrel comprising a head within the outer portion of the ferrule to coact with 110 the outer face of the shoulder and a block projecting from the head into the slot alongside the terminal therein, and an element engaging with the threads at the outer end of the ferrule and contacting with said head 115 to urge the wedge member inward.

In testimony whereof we affix our signatures.

WALTER O. SMITH. [L. S.]
JOSEPH E. GRENACHE. [L. S.]
